CONTROL FOR REFRIGERATING SYSTEMS

Alwin B. Newton, Minneapolis, Minn., assignor to
 Minneapolis-Honeywell Regulator Company,
 Minneapolis, Minn., a corporation of Delaware

Application July 12, 1940, Serial No. 345,252

21 Claims. (Cl. 62—4)

My invention relates to the art of refrigeration dealing more particularly with refrigerating apparatus of the compression type and automatic control therefor.

The primary object of my invention is to provide an automatic controller for refrigerating apparatus of the compression type such that whenever the compressor is stopped the evaporator temperature will rise to a value assuring that the evaporator becomes defrosted before the compressor can again be restarted.

Another object of my invention is to provide a suction pressure controller for compression type refrigerating apparatus in the form of a suction pressure responsive switch which is opened in response to the rise in suction pressure whenever the compressor is stopped by any automatic control device or other agency.

Another object is to provide a suction pressure controller in the form of a switch for starting the compressor at a predetermined high suction pressure and for stopping it at a predetermined relatively low suction pressure and having means for opening the switch in response to the rise in suction pressure whenever the compressor is stopped when the suction pressure responsive switch is still in closed position.

Another object is to provide a suction pressure responsive switch for controlling a compressor which starts the compressor at a predetermined relatively high suction pressure and stops it at a predetermined relatively low pressure and having a device responsive to compressor discharge pressure which may move the switch to open position so that the suction pressure must again rise to the predetermined relatively high value before it can be closed again.

Another object of my invention is to provide a switching mechanism embodying a switch operable between on and off positions by an operating member movable between corresponding positions and having a yieldable connection between the operating member and the switch whereby the operating member may operate the switch at a point between said positions if the operating member moves in a direction to operate the switch to a given position when the switch is already in that position.

Another object of the invention is to provide a switching mechanism embodying a switch operable between open and closed positions by a member movable between corresponding positions and a one way yieldable connection between the operating member and the switch whereby through the yieldable connection the operating

member may move the switch to one position when the operating member is moving in a direction to normally move the switch to the opposite position.

Another object of the invention is to provide a switching mechanism embodying a switch operable between closed and open positions by a member movable between corresponding positions and having a yieldable connection comprising a pivoted arm actuatable by the operating member whereby the switch may be operated to one position when the operating member is moving in a direction to normally operate the switch to the other position.

Another object of the invention is to provide in a switching mechanism a switch operable by a member movable between given positions and having a yieldable connection embodying a ratchet and a resilient pawl between the operating member and the switch so arranged that the operating member may open the switch when it is moving in a direction to normally close it.

For a better understanding of my invention reference may be had to the following detailed description and annexed drawing wherein the single figure represents an embodiment of my improved controller in combination with a compression type refrigerating system.

Referring to the drawing, numeral 10 designates generally a refrigerating system of the compression type. The system comprises a compressor 11, a condenser 12 and an expander located within a space or chamber 13 to be refrigerated, the compressor, condenser and expander being connected in the usual circuit relationship by pipes 14, 15, and 16 whereby refrigerant may be translated from the compressor to the condenser and the expander. An expansion valve 18 of any well known type may be interposed in the pipe 15 connected between the condenser and expander. The compressor 11 is driven by an electric motor 9 through a belt 17.

For controlling the compressor I have provided a controller which is primarily responsive to suction pressure and which is designated generally by the numeral 20. The controller is housed in a casing designated by the broken lines and includes a switch mechanism designated generally at 21. The switching mechanism 21 comprises a lever 22 pivoted on pin 23 and carrying mercury switch 24, the mercury switch being mounted in a suitable clip. The lever 22 is movable between fixed stops 19 and 29. The lower end of the lever 22 is shaped in the form of a yoke 55 having downwardly extending arms 25 and 26.

The arm 25 carries an adjustable screw 27 and the arm 26 carries an adjustable screw 28. Numeral 30 designates a disc mounted on a shaft which extends through the casing and which may be adjustable from the outside thereof. Eccentrically pivoted to the disc 30 by means of a pin 31 is an arm 32 the upper end of which bears against the screw 27. Numeral 33 designates a similar disc adjustable from outside the casing and to which is eccentrically pivoted an arm 34, the arm 34 being pivoted on a pin 35 carried by the disc 33. The upper end of arm 34 bears against screw 28 and the upper ends of both the arms 32 and 34 are normally urged away from each other and into engagement with their respective screws by a coil spring 35. Numeral 39 designates a lever arm pivoted on a pin 40 at the lower part of the casing, the upper part of the arm being disposed between the arms 32 and 34. The upper end of the arm 39 has small lateral extensions adapted to engage the arms 32 and 34.

Numeral 41 designates an expandable and contractible bellows element connected to the compressor suction pipe 16 by a tube 42. The movable end of the bellows 41 carries a stem 43 at the end of which is formed a knife edge engaged in a suitable notch near the lower end of the arm 39 whereby the pressure exerted by the bellows 41 urges the arm 39 in a counter-clockwise direction. The bellows 41 of course expands and contracts in accordance with the suction pressure existing in pipe 16. Numeral 44 designates a coil spring, one end of which is connected to the arm 39 and the other end of which is attached to an element 45 in screw threaded engagement with which is a screw 46 extending through a side wall of the casing whereby the screw may be adjusted from outside the casing so as to adjust the tension of spring 44. The spring 44 urges the arm 39 in a clockwise direction against the stem 43.

Numeral 50 designates a lever pivoted on a fixed pivot 51 and having a horizontal portion 52 adapted to bear against the arm 25 of lever 22. Numeral 53 designates a coil spring one end of which is attached to the pivot pin 51 and the other end of which engages the lever 50 so as to urge it in a counter-clockwise direction. Pivoted to the lower end of the lever 50 is an arm 54, the opposite end of which is disposed above the upper end of the arm 39, its lower edge having teeth formed therein so as to form a ratchet 55. The upper end of the arm 39 carries a resilient leaf or reed 56 which is adapted to engage the ratchet 55 as shown in the manner of a pawl.

Numeral 60 designates an expandable and contractible bellows similar to the bellows 41, this bellows being connected to the discharge pipe 14 by a tube 61. The movable end of the bellows 60 carries a stem 62 which bears against a lever 63 having a transverse portion 64, the lever 63 being pivoted on a pivot pin 65. The bellows urges the lever 63 in a counter-clockwise direction and the lever 63 is biased in a clockwise direction into engagement with the stem 62 by a coil spring 66 one end of which is attached to the lever and the other end of which is attached to a member 67, in screw threaded engagement with which is a screw 68 extending through a side wall of the casing. The screw 68 may be adjusted from outside the casing for varying the tension of spring 66. The transverse portion 64 of lever 63 extends to a point adjacent the upper part of lever 22 and as will presently be pointed

out may engage the lever 22 for operating the switch 24.

Numeral 70 designates a temperature responsive device comprising an expandible and contractible bellows 71 connected to a bulb 72 located within the refrigerated space by means of a tube 73. The bulb and bellows are filled with a volatile liquid so that the bellows expands and contracts in accordance with the temperature affecting the bulb 72. The movable end of the bellows 71 carries a stem 74 which actuates a pivoted lever 75 carrying a mercury switch 76, the lever 75 being biased against the stem 74 by a spring 77. When the temperature affecting the bulb 72 rises to a predetermined value the bellows 71 expands sufficiently to tilt the lever 75 in a counter-clockwise direction until the mercury switch 76 is closed, its electrodes being at its left end as shown.

When both the mercury switches 24 and 76 are closed the compressor motor 9 may be energized through a circuit as follows: wire 79, mercury switch 24, wire 80, mercury switch 76, wire 81, and the compressor motor 9 to wire 82, the wires 79 and 82 being connected to any suitable source of power not shown. With the parts in the position shown the compressor has been in operation and has been stopped by reason of the temperature within the refrigerated space falling to a low enough value to cause opening of the mercury switch 76. The suction pressure was at an intermediate value when the compressor was stopped, so that the arm 39 has assumed a position intermediate the arms 32 and 34. If the compressor had not been stopped by the thermostatic device 70 the suction pressure would eventually have fallen to a relatively low value so as to stop the compressor by opening switch 24 as will presently be described. However, with the parts in the position shown, with the compressor stopped, the suction pressure will begin to rise causing bellows 41 to expand moving arm 39 in a counter-clockwise direction. Pawl 56 being in engagement with the ratchet 55 will move arm 54 to the left rotating lever 50 in a clockwise direction as soon as the suction pressure starts rising. The portion 52 of lever 50 now will bear against arm 25 of lever 22 rotating the lever 22 in a counter-clockwise direction until it engages the stop 19 thereby tilting the mercury switch 24 into open position. After lever 22 has thus engaged the stop 19 its further rotation will be prevented and thus rotation of lever 50 in a clockwise direction by movement of the arm 54 to the left will be prevented. However, the suction pressure will continue to rise causing lever 39 to continue to move in a counter-clockwise direction, and due to its resiliency the pawl 56 will override the ratchet 55 as the arm 39 continues its leftward movement. The extent of the ratchet teeth 55 is such that after the suction pressure has risen to a value which may be 25 or 35 pounds for example, the pawl 56 bears against a smooth part of arm 54 so as not to be retarded. The teeth 55 are of such size that minor rises of suction pressure of five pounds or less will not operate the switch. When the suction pressure has risen to a predetermined relatively high value at which the evaporator 13 will have been defrosted, the upper end of arm 39 will engage the arm 32 moving the arm 32 in a counter-clockwise direction so that its upper end bearing against the screw 27 will move the lever 22 in a clockwise direction until it engages the stop 20 with the mercury switch 24 closed (as seen

on the drawing). The controller 20 will now be in a position wherein the compressor can be started whenever there is a demand from the thermostatic device 70, the position of the parts not changing in response to a further rise in suction pressure. Whenever the temperature in bulb 12 rises to a predetermined value causing closure of mercury switch 76 the above described circuit for the compressor motor 16 is completed. As soon as the compressor starts the suction pressure begins to fall thereby causing bellows 41 to contract and permitting movement of arm 39 in a clockwise direction, that is, to the right. The upper end of arm 39 will now move away from arm 32 without changing the position of the parts of the controller and when the suction pressure has fallen to a predetermined relatively low value if the compressor has not been stopped by the thermostatic device 70 the upper end of arm 39 will come into engagement with arm 34. As the suction pressure decreases arm 39 will move arm 34 in a clockwise direction, that is, to the right so that its upper end bearing against screw 28 will rotate lever 22 in a counter-clockwise direction until it engages stop 19 with the mercury switch 24 in an open position. Mercury switch 24 being thus opened the motor 16 will be deenergized thus stopping the compressor.

From the foregoing it will be seen that as long as the thermostatic device is calling for refrigeration the compressor will be operated between high an low limits of suction pressure. If the compressor is stopped by the thermostatic device when the suction pressure is at an intermediate value, then the mercury switch 24 will be opened by the ensuing rise in suction pressure and the suction pressure must then rise to a predetermined relatively high value before the mercury switch 24 will again be closed to permit restarting of the compressor. The suction pressure value at which the mercury switch 24 is closed is set high enough to insure that after each cycle of the compressor, the pressure within the evaporator will rise to a high enough value to insure that it becomes defrosted.

In the event that the compressor discharge pressure, that is, the head pressure should rise to an unduly high value the bellows 60 will be expanded moving lever 63 in a counter-clockwise direction until the portion 64 engages the lever 22 and rotates it about its pivot against the stop 19 thus opening the mercury switch 24. Thus the compressor may be stopped by reason of the head pressure rising to an unduly high value and compressor operation will be prevented as long as the head pressure is at a high enough value to maintain the lever 22 against the stop 19 with mercury switch 24 in the open position. If the mercury switch 24 has been opened by reason of the head pressure rising to an unduly high value the compressor can of course not be restarted until the suction pressure rises to a high enough value to cause defrosting of the evaporator at which the arm 39 acts to bring about closure of mercury switch 24 as above described. When the head pressure drops the bellows 60 contracts moving the portion 64 of lever 63 away from lever 22 and leaving the lever 22 in the position to which it was moved.

From the foregoing those skilled in the art will appreciate that I have provided a very useful and practical arrangement for controlling the compressor of a refrigerating system in such a manner that whenever the compressor is

stopped for any reason the evaporator will become defrosted before the compressor can be restarted. My improved controller is mechanical in its operation and is of a very inexpensive type of construction not employing delicate or uncertain mechanisms.

The single embodiment of my invention which I have disclosed is representative of its preferred form and application although it may take various other forms and numerous modifications may be made of it, wherefore my invention is not to be limited by my disclosure which is illustrated in accordance with the scope of the appended claims.

I claim as my invention:

1. In apparatus of the character described, in combination, switch mechanism, means for producing a switch actuating force adapted to be increased and decreased, a device arranged to cause said force to vary, said switch mechanism controlling the operation of said device, the force varying in one direction when the device is in operation and in the opposite direction when the device is not in operation, said switch mechanism being arranged to start the device when the force is at one value and to stop the device at a relatively different value of the force, additional automatic means for stopping the device, and means for operating said switching mechanism to stopping position in response to the change in force in said opposite direction resulting from stopping of the device by said automatic means.

2. In a refrigerating system having a compressor, a condenser, and an expander, means responsive to compressor suction pressure controlling the compressor, said means including a switch and operating means therefor whereby the switch is operated at a predetermined relatively high suction pressure to start the compressor and at a predetermined low suction pressure to stop the compressor, an additional automatic device for stopping the compressor, and means for operating said switch to stopping position in response to the resulting rise in suction pressure upon stopping of the compressor by said automatic device.

3. In a refrigerating system having a compressor, a condenser, and an expander, means responsive to compressor suction pressure controlling the compressor, said means including a switch and operating means therefor whereby the switch is operated at a predetermined relatively high suction pressure to start the compressor and at a predetermined low suction pressure to stop the compressor, an additional automatic device for stopping the compressor, means for operating said switch to stopping position in response to the resulting rise in suction pressure when the compressor is stopped by said automatic device, and means responsive to compressor discharge pressure for also operating said switch to stopping position.

4. In a refrigerating system having a compressor, a condenser, and an expander, means responsive to compressor suction pressure controlling the compressor, said means including a switch and operating means therefor whereby the switch is operated at a predetermined relatively high suction pressure to start the compressor and at a predetermined low suction pressure to stop the compressor, an additional automatic device for stopping the compressor, and means for operating said switch to stopping position in response to the rise in suction pressure which occurs when the compressor is stopped by said automatic de-

vice, said next to last mentioned means comprising a yielding one way connection between said suction pressure responsive means and switch.

5. In a refrigerating system having a compressor, a condenser, and an expander, means responsive to compressor suction pressure controlling the compressor, said means including a switch and operating means therefor whereby the switch is operated at a predetermined relatively high suction pressure to start the compressor and at a predetermined low suction pressure to stop the compressor, an additional automatic device for stopping the compressor, and means forming part of said suction pressure responsive means for operating said switch to stopping position in response to the rise in suction pressure which occurs when the compressor is stopped by said automatic device, said next to last mentioned means comprising a pawl and ratchet mechanism, said pawl being yieldable whereby after moving said ratchet to open said switch, the pawl overrides the ratchet teeth.

6. In a refrigerating system having a compressor, a condenser, and an expander, means responsive to compressor suction pressure controlling the compressor, said means including a switch and operating means therefor whereby the switch is operated at a predetermined relatively high suction pressure to start the compressor and at a predetermined low suction pressure to stop the compressor, an additional automatic device for stopping the compressor, means for operating said switch to stopping position in response to the rise in suction pressure which occurs when the compressor is stopped by said automatic device, said operating means comprising a first switch actuating arm, a second pivoted switch actuating arm, said second arm coacting with said first arm whereby movement of a part of said second arm in one direction moves the first arm in the opposite direction, an actuator for said arms, and means forming a yielding connection between said actuator and one of said arms whereby said actuator can move said one arm to operate the switch to stopping position, the yielding connection permitting continued movement of the actuator in the same direction whereby it can actuate the other arm to operate the switch to starting position.

7. In a refrigerating system having a compressor, a condenser, and an expander, means responsive to compressor suction pressure controlling the compressor, said means including a switch and operating means therefor whereby the switch is operated at a predetermined relatively high pressure to start the compressor and at a predetermined low pressure to stop the compressor, an additional automatic device for stopping the compressor, means for operating said switch to starting position in response to the rise in suction pressure which occurs when the compressor is stopped by said automatic device, said operating means comprising a first switch actuating arm, a second pivoted switch actuating arm, said second arm coacting with said first arm whereby movement of a part of said second arm in one direction moves the first arm in the opposite direction, an actuator for said arms, and means forming a yielding connection between said actuator and one of said arms whereby said actuator can move said one arm to operate the switch to starting position, the yielding connection permitting continued movement of the actuator in the same direction whereby it can actuate the other arm to operate the switch to stopping

position, said connection comprising a ratchet and a pawl adapted to override the ratchet teeth when the ratchet resists movement by the pawl.

8. In a refrigerating system having a compressor, a condenser, and an expander, means responsive to compressor suction pressure controlling the compressor, said means including a switch, a switch carrying element, stops between which said element moves, and a member movable between predetermined limits for engaging and actuating said element whereby said switch starts the compressor at a predetermined relatively high pressure and stops the compressor at a predetermined low pressure, an additional automatic device operable to stop the compressor, and means forming a yielding one way connection between said member and element whereby said member can move said element in one direction at any point between the limits of movement of said member if said element is not restrained from being moved by one of said stops, said releasable connection permitting movement of said member when said element is so restrained.

9. In apparatus of the character described, in combination, a switch having on and off positions, switch operating means responsive to pressure changes whereby the switch is operated to one position upon a rise in pressure and to another position upon a fall in pressure, and means whereby if there is a rise in said pressure when said switch is in said one position said operating means operates said switch to said other position.

10. In apparatus of the character described, in combination, a switch having on and off positions, switch operating means responsive to pressure changes whereby the switch is operated to one position upon a rise in pressure through a given range and to another position upon a fall in pressure through said range, and means whereby if the said pressure reverses its direction of change at an intermediate point in its range and changes a given amount the switch is operated to its opposite position.

11. In apparatus of the character described, in combination, a switch having on and off positions, switch operating means responsive to pressure changes whereby the switch is operated to one position upon a rise in pressure through a given range and to another position upon a fall in said pressure through said range, and means whereby if the pressure reverses its direction of change at an intermediate point in its range the switch is operated to its opposite position, said last means comprising a pawl and ratchet mechanism, the ratchet being movable by the pressure responsive means in one direction for operating the switch.

12. In apparatus of the character described, in combination, a switch having on and off positions, switch operating means responsive to pressure changes whereby the switch is operated to one position upon a rise in pressure through a given range and to another position upon a fall in pressure through said range, and means whereby if the said pressure reverses its direction of change at an intermediate point in its range the switch is operated to its opposite position, said last means comprising a pawl and ratchet mechanism, the ratchet being movable by the pressure responsive means in one direction for operating the switch, said pawl being resilient whereby it may override the ratchet teeth.

13. In apparatus of the character described, in

combination, a switch having on and off positions, switch operating means responsive to pressure changes whereby the switch is operated to one position upon a rise in pressure to a given value and to another position upon a fall in pressure to a given value, and means whereby said switch is operated to said other position upon rise in said pressure when said switch is in said one position.

14. In apparatus of the character described, in combination, a switch, force producing means for operating the switch whereby it has a given differential, and means forming an operative connection between the operating means and switch whereby if the force changes within said differential in a direction to normally move the switch to one position when the switch is already in that position, the switch will be moved to the opposite position.

15. In apparatus of the character described, in combination, a switch, an operating member for the switch for operating the switch between on and off positions as the member moves between corresponding positions, and means forming a yieldable connection between said member and switch whereby if said member moves in a direction to normally move said switch to a given position when it is already in that position said connecting means operates to move said switch to the opposite position, said yielding connection permitting continued movement of said member in said direction.

16. In apparatus of the character described, in combination, a switch, an operating member for the switch for operating the switch between on and off positions as the member moves between corresponding positions, and means forming a yielding connection between said member and switch whereby if said member moves in a direction to normally move said switch to a given position when it is already in that position said connecting means operates to move said switch to the opposite position, said yielding connection permitting continued movement of said member in said direction, said yielding connection comprising a pawl and ratchet mechanism, the pawl being yieldable so as to override the ratchet teeth.

17. In apparatus of the character described, in combination, a switch, an operating member for the switch for operating the switch between on and off positions as the member moves between corresponding positions, and means forming a yielding connection between said member and switch whereby if said member moves in a direction to normally move said switch to a given position when it is already in that position said connecting means operates to move said switch to the opposite position, said yielding connection permitting continued movement of said member in said direction, said connection means

comprising a pivoted arm, said arm being yieldably engaged with said member and said arm being so related to the switch so that when the switch is operated through the arm it is operated to a position opposite to that it would normally be operated to by movement of the member in the same direction.

18. In apparatus of the character described in combination, a switch, a switch carrying element, a stop cooperating with said element, a member movable between predetermined limits for engaging and actuating said element to operate the switch, and means embodying a yielding connection between said member and element whereby said member can move said element at any point between the limits of movement of said member if said element is not restrained by said stop, said yielding connection permitting movement of said member if said element is so restrained.

19. In apparatus of the character described in combination, a switch, a first switch actuating arm, a second pivoted switch actuating arm, said second arm coacting with said first arm whereby movement of a part of said second arm in one direction moves the first arm in the opposite direction, a switch operator for actuating said arms, and means forming a yielding connection between said operator and one of said arms whereby said operator can move said one arm to operate the switch to a given position, the yielding connection permitting continued movement of the operator in the same direction whereby it can actuate the other arm to operate the switch to the opposite position.

20. In apparatus of the character described in combination, a switch, a first switch actuating arm, a second pivoted switch actuating arm, said second arm coacting with said first arm whereby movement of a part of said second arm in one direction moves the first arm in the opposite direction, a switch operator for actuating said arms, and means forming a yielding connection between said operator and one of said arms whereby said operator can move said one arm to operate the switch to a given position, the yielding connection permitting continued movement of the operator in the same direction whereby it can actuate the other arm to operate the switch to the opposite position, said connection comprising a ratchet and a pawl adapted to override the ratchet teeth when the ratchet resists movement by the pawl.

21. In a refrigerating system, a switch in circuit with a refrigerant compressor, suction pressure responsive means for actuating the switch adapted to close the switch on a pressure rise and open it on a pressure fall, and means adapted to open the switch on a pressure rise when the switch is closed.
